US00D541778S

(12) **United States Design Patent** (10) **Patent No.:** **US D541,778 S**
(45) **Date of Patent:** **** May 1, 2007**

(54) **PORTABLE PHONE**

(75) Inventors: **Young-Sae Kim**, Palo Alto, CA (US);
Chi-Young Ahn, Seodaemun-Gu (KR);
Beom-Ku Han, Seoul (KR);
Chang-Hwan Hwang, Goyang-Si (KR)

(73) Assignee: **Samsung Electronics Co., Ltd.**,
Suwon-Si (KR)

(**) Term: **14 Years**

(21) Appl. No.: **29/234,754**

(22) Filed: **Jul. 22, 2005**

(30) **Foreign Application Priority Data**

Jan. 26, 2005 (KR) 30-2005-0002650

(51) **LOC (8) Cl.** **14-03**

(52) **U.S. Cl.** **D14/138**

(58) **Field of Classification Search** D14/341-347,
D14/138, 137, 147, 218; 455/575.1, 575.3,
455/575.4, 90.3, 556.1, 556.2; 379/443.01-433.13;
361/814; 348/14.02

See application file for complete search history.
